UNITED STATES PATENT OFFICE.

CONRAD MAYREIS, OF BEARDSTOWN, ILLINOIS.

IMPROVEMENT IN SHOE-FASTENINGS.

Specification forming part of Letters Patent No. **175,367**, dated March 28, 1876; application filed January 29, 1876.

To all whom it may concern:

Be it known that I, CONRAD MAYREIS, of Beardstown, in the county of Cass and State of Illinois, have invented a new and Improved Shoe-Fastening, of which the following is a specification:

My invention consists of a fine wire fastened at the ends, and one or two intermediate points to the shoe, one on each side of the slit, with metal fastening-clasps on the lower portions of the wires and metal and rubber, or other elastic clasps on the upper portion, making a simpler and less laborious fastening to operate, than the fastenings now in use.

Figure 1 is a top view of a shoe, having my improved fastening. Fig. 2 is a section on line *x x*, and Fig. 3 is a section on line *y y*.

Similar letters of reference indicate corresponding parts.

A represents the wires which are fastened to the parts B of the shoe at C. D represents the metal clasps to the lower part, and E the elastic clasps to the upper part, said clasps be-

ing so applied to the wires that they can slide up and down on them freely between the fastenings C of the wires. The elastic fastenings are only needed in the upper part when greater allowance must be made for the opening of the slit to put in the foot and take it out.

The clasps are fastened on the wires low down where they come close together, and are then shoved upward to draw the shoe tight, and to unfasten it they are first shoved down as far as they will go, when they disconnect easier.

Having thus described my invention, I claim as new and desire to secure by Letters Patent—

The combination of wires A and clasps D and E, with a shoe, for the purpose of fastening it, substantially as specified.

CONRAD MAYREIS.
